S. D. JACOBSON

SAFETY DEVICE FOR FLYING MACHINES

Filed March 25, 1922

Patented July 10, 1923.

1,461,216

UNITED STATES PATENT OFFICE.

SIDNEY D. JACOBSON, OF NEW YORK, N. Y.

SAFETY DEVICE FOR FLYING MACHINES.

Application filed March 25, 1922. Serial No. 546,571.

To all whom it may concern:

Be it known that I, SIDNEY D. JACOBSON, a citizen of the United States, and a resident of the borough of Manhattan, city, 5 county, and State of New York, have invented an Improvement in Safety Devices for Flying Machines, of which the following is a specification.

My present invention relates to devices 10 intended to be used in connection with heavier-than-air flying machines, such as airplanes of the monoplane and biplane types for restoring equilibrium to the flying machine after it has been damaged, and 15 also for increasing the buoyancy of such machines, and even enabling the same to act in the manner of a parachute, when the machine has been damaged or even rendered altogether incapable of continuing the operation of flying.

It is an object of the present invention to provide devices of the general character specified above which shall accomplish the desired purpose in a certain and efficient 25 manner, which shall provide additional means of safety for flying machines and for the occupants thereof, and which shall at the same time be simple in construction, which shall interfere as little as possible 30 with the normal act of flight when the machine is in proper condition for flying, and which shall be certain and efficient in operation for the desired purpose.

By way of example, I shall, in the accompanying specification, describe, and in the annexed drawing show, several illustrative embodiments of the present invention. It is, however, to be understood that 35 my invention is not limited to the embodiments thereof which are herein shown and described for purposes of illustration only.

While the present invention may be applied with equal success to various types of heavier-than-air flying machines, it finds 45 particularly successful application when used in connection with airplanes, and is so shown applied.

Referring to the drawings, wherein I have illustrated two forms of my invention 50 as applied to a biplane:

Figure 1 is a view, in side elevation, of the airplane with my device applied thereto, the balloon members being shown in deflated or inoperative position in full lines, 55 and in inflated or operative position in dotted lines;

Figure 2 is an enlarged view, in perspective, of a series of balloon members in inflated or operative position;

Figure 3 is a cross sectional view, on an 60 enlarged scale, of one of the balloon members in the act of being inflated;

Figure 4 is a detailed cross sectional view, partly in elevation, of one form of valve member that may be employed for controlling the admission and exhaust of the inflating gas;

Figure 5 is a detailed cross sectional view, partly in elevation, of one of the hollow struts used for the passage of the inflating 70 gas to the balloon members;

Figure 6 is a detailed view, in side elevation, partly broken away, showing one form of means that may be employed for maintaining the balloon members in deflated or inoperative position; and 75

Figure 7 shows, in side elevation, a modified form of balloon member.

Referring to the illustrative embodiment of my invention shown in Figures 1 to 6, 80 inclusive, 10 indicates the body or fuselage of the airplane, herein shown as being of the two-seater type. The fuselage 10 is provided as usual with the runner wheels 11, the propeller 12 and the tail and rudder 13. 85 The engine, which is generally indicated by reference character 14, is, as usual, located in the forward end of the body of the airplane.

At 20 I have indicated a lower, and at 21 90 an upper, plane of the biplane. These planes are, as more clearly shown in Figure 3 of the drawing, made in the usual manner by winding properly "doped" or treated linen or other fabric 22, over rods 23 and 24, so that a space 25 is provided within each plane for a purpose subsequently to be set forth in detail.

The planes 20 and 21 are maintained in proper spaced relation by means of front 100 struts 30, and rear struts 31. The rear struts 31 are hollow, as more clearly indicated in Figures 3 and 5 of the drawing. Within each hollow rear strut 31 is a tube 32 for conducting inflating gas from the gas 105 tank 40, securely fastened to the lower or under side of the fuselage 10, to the balloon members 50. There being three balloon members shown, and but two rear hollow struts, one of the rear hollow struts may contain two gas-conducting tubes 32 which lead 110 separately to their respective balloon mem-

bers 50, if it is desired to keep said balloon members out of direct communication with each other.

The gas tank 40 contains any suitable inflating gas, such as hydrogen or helium. It is also preferred that the tank 40 shall have associated therewith a gas pressure gauge which is so positioned that it may be directly viewed by the pilot in the airplane so that he may at any time determine the condition of the pressure of the gas in the tank 40.

Each of the balloon members 50, of which three are shown, comprising a right-hand member 50^a, a central member 50^b, and a left-hand member 50^c, comprises a false upper plane section 51 hinged, as at 51', to the upper plane 21 as viewed from the seat of the aviator. Attached to the false upper plane member 51 is an end balloon section 52 of any suitable flexible and gas-tight fabric, and two side balloon sections 53. The members 51, 52 and 53, together with the upper face of the upper plane 21, form a gas-tight compartment or balloon cavity for receiving the gas intended to inflate the same.

I prefer that the fabric of which the members 52 and 53 are made shall be of as strong a material as possible, preferably of a puncture-proof cloth of the sort which is well known to those skilled in this art. I also prefer that each gas bag or balloon member 50 shall be reenforced and surrounded with a network of ropes or tapes which shall take up and distribute the load carried by each balloon member so as to relieve the same from undue strain and stress, all of which will be familiar to those skilled in this art. Each balloon member should also be provided with the usual vent for permitting the gradual escape of the inflating gas from the same, and with a rip for permitting, in cases of necessity, the sudden and complete escape of the inflating gas from any particular balloon member 50.

As is more clearly shown in Figure 3 of the drawing, the end balloon section 50 and the side balloon sections 53 are so constructed and arranged as to be neatly folded in place in the manner of an accordion pleat when each balloon section is in its deflated or inoperative condition. It will also be noted that I prefer a reenforcing rod 54 which is associated with the outer ends of the false upper plane members 51 for maintaining said plane members in alignment. This arrangement strengthens the balloon members, and guards the same against undue liability to be warped or injured in use.

In order to maintain each balloon member properly deflated and neatly in position on top of the upper plane 21 so that the normal operation of flying will not be inter-

fered with, I provide a locking member 55 pivoted as at 56 to the upper plane, and attached, as at 57, by means of a wire 58 to the operating lever 60, as more clearly shown in Figures 1, 4 and 6 of the drawing.

Communicating with the gas tank 40, as by means of a pipe 70, is a valve chamber 71 provided with a valve cavity 72 having an open air outlet 73 and a three-way valve member 74 adapted to be operated in a rotative manner, as by means of the operating lever 60. The valve 71 is provided with a pipe 75 which leads, by means of three branch pipes 76^a, 76^b, and 76^c, to the respective pipes 32 within the hollow struts 31 to 80 the respective balloon members 50^a, 50^b and 50^c.

Where, as may be preferred, the pipes 32 communicate directly with the respective balloon sections so that said sections are out of direct communication with each other, I prefer to provide each pipe 32 with a check valve so constructed and arranged that gas will flow but one way from the pressure tank into the balloon members, thus rendering said members substantially independent of each other, and enabling any one or two of such members to operate in the contingency that one or more of the balloon members may be injured and thus unable to function. In such a case each check valve may be provided with manually operable means for rendering the same inoperative so as to release the inflating gas from the balloon members, such releasing means being in addition to the vent and the rip already described above.

Where desired, I may provide manually operable means to permit slow inflation of any one or two, or all three, of the balloon members 50. This may be desirable in those cases where, due to a peculiar injury to the airplane, it may be desirable to provide additional buoyancy at one or the other side of the plane, in order to restore its equilibrium, rather than evenly over the whole upper plane.

The operation of the device described above and the advantages of the same in use may briefly be summarized as follows: When, for any reason, as by reason of the occurrence of an accident which threatens to precipitate the plane to the earth, or, in a less critical case, undesirably affects the equilibrium of the plane, it may be desired to render the balloon members operative, the pilot operates the lever 60 away from him, thus releasing the hook 55 from the upper false plane members 51, and bringing the gas tank 40 into communication with the balloon members 50 by means of the valve 71 and the pipes 32.

As already stated, these pipes may be continued so as to be brought into direct communication with the respective balloon

members 50, which in this case are out of communication with each other, by extending said pipes 32 through the upper layer of the fabric forming the upper plane 21. 5 However, as shown, the three balloon members are in communication with each other through the partition 26 in the space 25 within the upper plane 21, said partition 26 being provided with perforations 27 and 10 with an upper opening 28 leading to the space within each balloon member 50.

Upon establishing communication between the gas tank 40 and any one or two, or all three, of the balloon members 50, since said 15 balloon members are now free to be inflated by reason of the release of the locking means 55, the same will expand at a rate, slow or fast, as desired, dependent upon the degree to which the valve 71 has been opened by 20 the pilot in the machine. This operation of inflation will take place in a certain and efficient manner due to the particular shape and arrangement of the balloon members 50, and particularly of the end balloon sections 52 and the side balloon sections 53, which, as already described above, are in the form of accordion pleats when the balloon members are in deflated condition. 25

Upon the inflation of the desired number 30 of balloon members, in accordance with the particular needs of the machine, dependent upon the cause and location of the force disturbing its normal equilibrium, the equilibrium of the machine will be restored, its 35 buoyancy substantially increased, and the arrangement of the respective balloon members will be such as to retard the drop of the machine and to cause the same to act somewhat in the manner of a parachute.

40 It will be noted that, by means of the provision of the false upper plane members 51, the various balloon members will be neatly and securely folded down in place when in deflated or inoperative position. In this 45 way, the safety devices provided by me will interfere little, if at all, with the normal flying operation of the machine. Furthermore, by means of the check valves which I have provided, if one or two, or all three, 50 of the balloon members are rendered inoperative by reason of some injury to the same which renders them incapable of being inflated, the remaining balloon members may be operated and may of themselves serve to 55 save the airplane and the occupants thereof.

It will also be noted that by a single operation of the operating lever 60 I release 60 the locking member 55, thus enabling the balloon members to be inflated, and also bring such balloon members into communication with the gas in the tank 40.

The foregoing and other advantages, 65 which will readily occur to those skilled in the art to which the present invention relates, make this device one of great prac-

tical value, and the machine to which it is applied of unusual safety. The device is at the same time exceedingly simple, while being also certain and efficient in operation, light in weight, and interfering as little as 70 possible with the normal flying operation of the machine.

The present invention may be applied with equal success to lighter-than-air flying machines, such as observation and spherical, 75 cigar-shaped, or other passenger balloons and dirigibles. The balloon members 50^a, 50^b and 50^c, may be of any suitable form or shape, such as spherical, as shown at 50' in Figure 3 of the drawing, or cigar-shaped 80 so with the length of the balloon member in such a case extending in the direction of the length of the flying machine.

While the lever 60 has been described above as being operable in a forward direction, it is to be understood that it may be so constructed and arranged as to be operated in a backward direction. It is also to be understood that the inflating gas, such as the hydrogen or helium, is contained in the 90 storage tank 40 under considerable pressure, and that while the gas may be released for admission to the balloon members gradually, it may also be so released suddenly for the sudden and complete inflation of the 95 balloon members substantially instantaneously in case of an emergency requiring such instantaneous inflation. It is also to be understood that, if desired, as many storage tanks for inflating gas under pressure may 100 be used as there are balloon members or compartments.

What I claim is:

1. In a flying machine, a source of supply of inflating gas under pressure, a plurality of inflatable members attached to said flying machine, locking means for normally maintaining said inflatable members in deflated condition, means for releasing said locking means to permit the inflation of said inflatable members, and means associated with said releasing means and cooperating therewith for bringing said inflatable members into communication with said source of supply of inflating gas to inflate said inflatable 115 members.

2. In a flying machine, a source of supply of inflating gas under pressure, a plurality of inflatable members attached to said flying machine, each of said inflatable members comprising a false plane member and associated flexible members forming a balloon compartment, and means for bringing said inflatable members into communication with said source of supply of inflating gas 125 to inflate said inflatable members.

3. In a flying machine, a source of supply of inflating gas under pressure, a plurality of inflatable members attached to said flying machine, each of said inflatable members 130

- 4
- comprising a false plane member and associated flexible members forming a balloon compartment, locking means for normally maintaining said inflatable members in deflated condition, means for releasing said locking means to permit the inflation of said inflatable members, and means for bringing said inflatable members into communication with said source of supply of inflating gas to inflate said inflatable members.
  - 5. In a flying machine, a source of supply of inflating gas under pressure, a plurality of inflatable members attached to said flying machine, each of said inflatable members comprising a false plane member and associated flexible members forming a balloon compartment, locking means for normally maintaining said inflatable members in deflated condition, means for releasing said locking means to permit the inflation of said inflatable members, and means associated with said releasing means and cooperating therewith for bringing said inflatable members into communication with said source of supply of inflating gas to inflate said inflatable members. 25
  - 10. 4. In a flying machine, a source of supply of inflating gas under pressure, a plurality of inflatable members attached to said flying machine, each of said inflatable members comprising a false plane member and associated flexible members forming a balloon compartment, locking means for normally maintaining said inflatable members in deflated condition, means for releasing said locking means to permit the inflation of said inflatable members, and means associated with said releasing means and cooperating 30
  - 15. 5. In a heavier-than-air flying machine, a plane, a false plane member attached thereto, and members of flexible gas-tight fabric associated with said plane and with said false plane member and forming therewith an inflatable balloon compartment. 35
  - 20. 6. In a heavier-than-air flying machine, a plane, a false plane member hingedly attached thereto at the forward edge thereof, and members of flexible gas-tight fabric associated with said plane and with said false plane member and forming therewith an inflatable balloon compartment. 40

In testimony whereof, I have signed my name to this specification this 14th day of March, 1922.

SIDNEY D. JACOBSON.
